(57) **CLAIM**

The ornamental design for the inflatable dock, as shown and described.

DESCRIPTION

FIG. 1 is a top perspective view of the inflatable dock showing the new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof;

FIG. 7 is a bottom view thereof; and,

FIG. 8 is a bottom perspective view thereof.

The broken line showing on the inflatable dock is for the purpose of illustrating portions of the inflatable dock that form no part of the claimed design.
